(57) **CLAIM**

The ornamental design of a digital fuel meter, as shown and described.

DESCRIPTION

FIG. 1 is a perspective view of a digital fuel meter;

FIG. 2 is a forward view of the digital fuel meter of FIG. 1;

FIG. 3 is a rear view of the digital fuel meter of FIG. 2;
FIG. 4 is a bottom view of the digital fuel meter of FIG. 2;
FIG. 5 is a top view of the digital fuel meter of FIG. 2;
FIG. 6 is a left-hand side view of the digital fuel meter of FIG. 2;
FIG. 7 is a right-hand side view of the digital fuel meter of FIG. 2;
FIG. 8 is a forward view of another embodiment of a digital fuel meter;
FIG. 9 is a rear view of the digital fuel meter of FIG. 8;
FIG. 10 is a bottom view of the digital fuel meter of FIG. 8;
FIG. 11 is a top view of the digital fuel meter of FIG. 8;
FIG. 12 is a left-hand side view of the digital fuel meter of FIG. 8;
FIG. 13 is a right-hand side view of the digital fuel meter of FIG. 8;
FIG. 14 is a forward view of another embodiment of a digital fuel meter;
FIG. 15 is a rear view of the digital fuel meter of FIG. 14;
FIG. 16 is a bottom view of the digital fuel meter of FIG. 14;
FIG. 17 is a top view of the digital fuel meter of FIG. 14;
FIG. 18 is a left-hand side view of the digital fuel meter of FIG. 14;
FIG. 19 is a right-hand side view of the digital fuel meter of FIG. 14;
FIG. 20 is a forward view of another embodiment of a digital fuel meter;
FIG. 21 is a rear view of the digital fuel meter of FIG. 20;
FIG. 22 is a bottom view of the digital fuel meter of FIG. 20;
FIG. 23 is a top view of the digital fuel meter of FIG. 20;
FIG. 24 is a left-hand side view of the digital fuel meter of FIG. 21; and,
FIG. 25 is a right-hand side view of the digital fuel meter of FIG. 21.
